(57) CLAIM

The ornamental design for a modular sofa, as shown and described.

DESCRIPTION

FIG. 1 is a perspective view of the modular sofa showing my new design;

FIG. 2 is an exploded perspective view of the modular sofa of FIG. 1, showing all the components separated;

FIG. 3 is a front elevational view of the modular sofa of FIG. 1;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The jagged lines shown on the four larger back cushions in the drawings depict surface ornamentation and form part of the claimed design.
